UNITED STATES PATENT OFFICE.

GEORGE F. DYER, OF SIERRA MADRE, CALIFORNIA.

SEPARABLE HINGE.

Application filed January 29, 1924. Serial No. 689,287.

This invention relates to hinges and particularly to those types of hinges which are used to detachably secure a member to a supporting structure.

5 In buildings it is desirable to have the various closing members, such as the doors, swinging windows and swinging screens, detachable. Hinges of the ordinary type are constructed so that the hinging pin is removable and the swing member is thereby rendered detachable. These hinges are practical when used with the pin in vertical disposition, but when the swinging member is hinged horizontally and the hinge pin 10 rests in a horizontal plane, there is a tendency for the pin to work loose.

It is the principal object of my invention to provide a separable or detachable hinge which may be used for the horizontal hinging of the various heretofore mentioned members.

Additional objects and the specific advantages of my invention will be made evident hereinafter.

25 Referring to the drawing which is for illustrative purposes only,

Fig. 1 is a view illustrating the utility of the invention, showing my device used for hanging a window screen.

30 Fig. 2 is a section taken as indicated by the line 2—2 of Fig. 1.

Fig. 3 is a section taken as indicated by the line 3—3 of Fig. 2.

Fig. 4 is a plan view of my invention showing the separable parts ready to be placed in securing relationship.

Fig. 5 is a plan view of my invention with the securing pin removed.

As shown in the drawings, my invention 40 provides a primary member 11 which is adapted to be secured to a swingable member, such as the screen 12, as shown, by the screws 14. At the upper part of the primary member, there is formed a central tubular portion 16 which may be formed by rolling an extending portion of the member. The secondary member 17 has formed in a similar manner outer tubular portions 18 which cooperate with the tubular portion 16 and the

50 pivot or hinge pin 19, which extends through these tubular portions, to form the pivot 20 of the hinge. On a plane substantially perpendicular to the pivot 20 and also substantially vertical, the outwardly projecting channel portions 22 and 23 and the inwardly depressed channel portion 24 are

formed. In the attachment plate 25, which is secured to the window casing 26 by suitable screws 27, are formed outwardly pressed channel portions 28 and 29, over which the 60 channel portions 22 and 23 rest and the inwardly pressed channel portion 30 in which the channel portion 24 rests. A securing pin 32 is extended through the outwardly pressed channel portions 28 and 29 and the inwardly 65 pressed channel portion 24, securing the secondary member 17 and the attachment plate 25 rigidly together as shown in Figs. 1, 2 and 3, the portions 22 and 23 fitting over the portions 28 and 29 and serving as centralizing 70 means for the secondary member and the attachment plate, and preventing them from being skewed.

In installing the hinge the primary member 11 is first secured to the screen frame 12 75 in the manner previously described, the secondary member 17 being hinged thereto, and the attachment plate 25 is secured to the encasement 26 as previously described. Next, the hinge parts are aligned as shown in Fig. 80 4, and then the parts are assembled as in Fig. 5, the portions 22 and 23 fitting over the portions 28 and 29, thereby serving as centralizing means, and the portion 24 fitting in the portion 30. The pin 32 is then 85 passed through the channel portions 28, 29 and 24 which holds the secondary member 17 and the attachment plate 25 securely in place. If it is desired to have the screen hinged at the bottom, the parts are reversed 90 relative to the screen and the encasement, that is, the primary member 11 is secured to the encasement 26 and the attachment plate 25 is secured to the screen frame 12 in order that the hinge may rest in the same 95 position as shown in the drawings.

Owing to the fact that the pin 32 sets in vertical position the pin will not work from place but will tend to remain seated. By making a hinge of this character, I have 100 provided an article which is of extensive use in the building trades, and because of the simple construction thereof it may be offered to the users at a low cost.

I claim as my invention:

1. A hinge comprising: a primary member and a secondary member hinged together by a longitudinal pin; an attachment plate; said secondary member and said plate being respectively provided with cooperating means 110 to receive an attaching pin extending substantially at right angles to said longitudinal

pin; and a pin perpendicular to said hinging pin for detachably securing said secondary member and said attachment plate together, said cooperating means comprising interfitting channels stamped in said secondary member and said plate.

2. A hinge comprising: a primary member; a secondary member hinged to said primary member having upper and lower outwardly formed channel portions and a central inwardly formed channel portion; and an attachment plate having upper and lower

outwardly formed channel portions and a central inwardly formed channel portion, said secondary member channels and said attachment member channels being in cooperating relationship; and a pin extending through said channels for securing said attachment plate and said secondary member together.

In testimony whereof, I have hereunto set my hand at Los Angeles, California, this 23rd day of January, 1924.

GEORGE F. DYER.
